UNITED STATES PATENT OFFICE.

HARRY HACKMAN, OF TORONTO, ONTARIO, CANADA.

HOT-WATER CIRCULATING SYSTEM.

1,404,365.

Specification of Letters Patent. Patented Jan. 24, 1922.

Application filed April 19, 1920. Serial No. 375,051.

To all whom it may concern:

Be it known that I, HARRY HACKMAN, a subject of the King of Great Britain, and resident of the city of Toronto, county of York, Province of Ontario, in the Dominion of Canada, have invented certain new and useful Improvements in Hot-Water Circulating Systems, described in the following specification and illustrated in the accompanying drawings, that form part of the same.

The principal objects of this invention are, to ensure a constant supply of hot water at the taps which may be obtained immediately upon opening the tap and to obviate the loss of heat through allowing the hot water in the pipes to cool.

A further object is to minimize the settling of dirt, scale, etc., within the pipes, and to provide a circulating system which can be readily adapted to any hot water system.

A still further object is to eliminate the necessity of the use of a back flow valve to prevent the back flow of cold water.

The principal feature of the invention consists in the novel arrangement of a return circulating pipe from the dead end of the system to the heater coil whereby a continuous circulation through the pipes is maintained.

In the drawings, Figure 1 is a diagrammatic elevational view illustrating the application of my invention to the water heating system.

Figure 2 is a plan sectional view of the furnace and hot water reservoir showing the arrangement of the heater coil.

It is well known that the ordinary system of piping dwellings with the hot water reservoir in the basement has a very objectionable feature, in that when hot water is required the cold water in the pipes has first to be emptied out and though only a small quantity of hot water may be required the whole length of pipe has to be filled and the heat in such water supply is wasted through lying in the pipe and cooling. It is therefore desirable to maintain a constant circulation of the water through the supply pipes and I have devised the present system as being very simple and effective.

The arrangement is diagrammatically

illustrated in the drawings where 1 represents the hot water reservoir having the usual cold water supply 2 and hot water pipe 3 which leads from the top of the reservoir to the various taps through the house.

At the dead end of the system which is usually the bath-room the hot water supply 3 connects with the faucet 4.

A T connection 5 is arranged in the faucet connection and a return circulation pipe 6 is connected to said T and extends downwardly and connects with a T 7, the branch 8 of which connects with the bottom of the reservoir and the branch 9 connects with the lower end of the heater coil 10 arranged in the furnace. The upper end 11 of the heater coil is connected into the side of the reservoir.

This arrangement of pipe provides that the supply to the heater coil 10 must be taken either from the bottom of the reservoir or from the return pipe 6 and as the water in the return pipe 6 will always be warmer than the water from the bottom of the reservoir the natural flow will be from the pipe 6 through the coil to the reservoir and as the water in the return pipe will through radiation be cooler than the water in the pipe 3, the natural circulation is established, the cooler water falling until it is passed through the heater coil when it is again forced into circulation.

This arrangement eliminates any necessity for a back flow valve as there cannot possibly be any back flow of cold water, and such a construction will maintain a constant supply of hot water at the faucet and the heating of the water will be accomplished quicker and with less loss than when cold water is taken directly from the bottom of the boiler to the heater coil.

What I claim as my invention is:—

1. In a hot water circulating system, the combination of the reservoir and a heater coil having its upper end connected solely intermediate of the height of said reservoir, a hot water pipe leading from the top of the reservoir, a return circulation pipe leading from the dead end of the hot water pipe and connected directly to the lower end of the heater coil and to the lower end of the reservoir in a closed circuit.

2. In a hot water circulating system, the combination of the hot water reservoir, a hot water feed connected to the top of the reservoir, a heater coil having its upper end connected to the side of the reservoir, a pipe leading upwardly from the bottom of the reservoir, a **T** connection connecting said upper end of the pipe with the lower end of the heater coil, and a return circulation pipe connected to said **T** and connected with the upper end of the hot water feed pipe from the reservoir.

HARRY HACKMAN.
